(57) **CLAIM**

The ornamental design for a medical adhesive applicator, as shown and described.

DESCRIPTION

FIG. 1 is a right side elevational view of a first embodiment of a medical adhesive applicator showing the new design; FIG. 2 is a rear elevational view thereof; FIG. 3 is a left side elevational view thereof; FIG. 4 is a front elevational view thereof; FIG. 5 is a top plan view thereof; FIG. 6 is a bottom plan view thereof; FIG. 7 is a perspective view thereof; and FIG. 8 is a perspective view thereof.

FIG. 9 is a right side elevational view of a second embodiment of the medical adhesive applicator of the new design; FIG. 10 is a rear elevational view thereof; FIG. 11 is a left side elevational view thereof; FIG. 12 is a front elevational view thereof; FIG. 13 is a top plan view thereof; FIG. 14 is a bottom plan view thereof; FIG. 15 is a perspective view thereof; and, FIG. 16 is a perspective view thereof.

The broken lines shown in FIGS. 1-16 illustrate portions of the medical adhesive applicator that form no part of the claimed design.
